SHADE OR BLIND FASTENER

George D. Dodge, Evanston, Ill.

Application September 29, 1937, Serial No. 166,450

4 Claims. (Cl. 156—26)

The present invention relates to a shade or blind and more particularly to window shades or blinds for use in railway cars and other situations where there is an increased tendency for dis-
placement and disarrangement.

It is an object of the present invention to pro-
vide an improved control mechanism for a blind
or shade which will maintain the said blind and/
or shade level at all times.

An additional object of the present invention
is to provide an improved control bar for a blind
or shade which will permit selective locking of
the device in any predetermined longitudinal po-
sition by convenient manual control means.

It is furthermore an object of the present in-
vention to provide a control bar for a blind or
shade having means positively engaging into the
surrounding frame and securing the bar thereto
against slidable movement at all times, which
means may be selectively interlocked with the
bar to affix the bar in any preselected position.

Still another object of the present invention is
to provide a blind or shade having thereon rotat-
able means interlocked with the frame to cause
rotation when moved relatively thereto in com-
bination with means to selectively lock the rotat-
able means against rotation when it is desired to
position the shade.

Numerous other objects and advantages will
more fully appear during the course and progress
of the following specification.

Referring to the drawing:

Fig. 1 is a front elevational view of a shade con-
structed in accordance with the present invention.

Fig. 2 is a sectional elevation taken on the line
2—2 of Fig. 1.

Fig. 3 is a detail sectional elevation taken on
the line 3—3 of Fig. 2.

Fig. 4 is a sectional elevation taken on the line
4—4 of Fig. 1.

Fig. 5 is a sectional elevation on the line 5—5
of Fig. 1.

The window shade, shown in Figs. 1 to 5 for the
purpose of illustrating the present invention,
comprises a flexible fabric portion 10 supported
at its upper end on the spring roller 12 which is in
turn supported for rotation in the window frame
14. The guide-ways 20 are undercut as at 22 to
engage a corresponding shoulder on the slide
members 18 for maintaining the latter units in
the guide-ways 20 against inadvertent displace-
ment. The guide-ways 20 are also lined with a
layer 24 of suitable sheet material which, in the
preferred embodiment, comprises a layer of fibre

for deadening sounds and resiliently dissipating
clashing incident to the actuation of the device.
Preferably also the tube 16 is rigidly fastened to
the slide members 18 as by brazing although it
may, if desired, merely be positioned rotatably in
the opposed apertures.

According to the preferred embodiment the
tubular member 16 is completely enclosed in the
material forming the fabric portion 10 of the
shade. As more completely shown in Fig. 5, the 10
fabric is at this point doubled, the forward sheet
26 passing about the forward face of the tube 16.
A curved plate 28 is secured over the sheet 26
where it passes about the tube 16 at the central
portion only for the purpose of positioning the 15
relative parts and forming an attractive finished
appearance about the manual control portions of
the control bar. It is to be noted that the tube
16 and the forward sheet 26 are cut away at 38
and the curved front plate 28 apertured at 40 to 20
permit passage of the manual control handles to
be hereinafter described.

The plate 28 is held in place by machine screws
30 passing therethrough and engaging into
threaded apertures in the rear clamping plate 32 25
which engages about the rearward face of the
tube 16. The rearward sheet of material form-
ing the fabric portion of the shade encloses the
rear surface of the tube 16 as well as the clamp-
ing plate 32 to conceal the entire structure from 30
the rear direction, being secured to the forward
sheet 26 by stitching 36. It will be apparent
from the above disclosure that the locking bar
may be mounted upon the sheet in various other
ways or may be combined with a blind of any de- 35
sired type.

Means is provided to accurately position the
control bar and comprises a central shaft 42
rotatably mounted along the axis of the tube 16
and having pinned thereto at either end the pin-
ions 44 which are engaged continually with the
vertically extending racks 45 mounted rigidly on
the inner forward face of the vertically extending
guide-ways 20. Since the pinions are iden-
tical in structure and continually mesh with the
racks 45, it will be apparent that the bottom con-
trol bar will always remain horizontally arranged
regardless of its vertical position with respect to
the window frame.

Manual means to control the locking of the 50
shaft 42 and thus the positioning of the shade,
comprises opposed sleeves 46 and 48 positioned
within the tube 16 and engaging about the shaft
42 to provide bearing portions therefor when the
latter member is in rotation. The sleeve 46 is 55

rigidly brazed, soldered or welded to the tube 16 and has a forwardly projecting finger portion 50 which extends through the cut-away portion 38 and the aperture 40 into a convenient position for 5 manual contact. The sleeve 48, axially spaced therefrom, is slidably mounted with respect to the axis of the tube 16 and the shaft 42, but is normally pressed to the right and remotely away from the sleeve 46 by means of the compression 10 spring 52. In this position notches 54 will engage the opposite end of the pin 56 passing through the shaft 42 and secured for rotation therewith. The manual control finger 58 extends forwardly through the cut-away portion 38 15 and through the aperture 40 in the curved front plate 28 and is spaced in aligned relationship from the fixed control finger 50. The projecting portion 60 merely serves to interiorly cover the aperture 40 at all times to conceal the operating 20 mechanism.

In operation of the present device, it will be apparent that the control bar, and accordingly the lower end of the shade, at all times runs upon and is positioned by the racks 45 and the guideways 28. When the parts are in the position shown by the solid lines in Fig. 4, rotation of the shaft will be prevented by engagement of the notches 54 in the sleeve 48 with the ends of the pin 56. Rotational movement of the sleeve 48 25 with respect to the tube 16 and the shade is prevented by the forwardly extending finger portion 58 which is positioned in the aperture 40 of the front curved plate 28 and this arrangement of the parts is maintained by means of the compression spring 52.

When it is desired to vertically adjust the shade, the control fingers 50 and 58 may be manually grasped and pressed together against the resilient action of the spring whereupon the control finger 58 will move to the dotted-line position indicated in Fig. 4, freeing the ends of the pin 56 from the notches 54 and thus permitting the shaft 42 to rotate freely with respect to its supports. With the parts in this position, the 40 control bar may be freely actuated either upwardly or downwardly, during which time the pinions 44 will rotate so as to travel upon the racks 45. After adjustment, the control bar may be locked in a preselected position by releasing 45 the control fingers 58 whereupon the sleeve 48, under the influence of the spring 52, will again engage the pin 56 and lock the shaft 42 therewith against rotation.

The invention provides fastening means for a shade or blind which will cause the shade or blind to be maintained in proper horizontal position at any selected height. The blind or shade is prevented from moving out of its guides and is positively prevented from creeping, as the blind or shade cannot be operated except when the thumb piece 59 is pressed to release the locking engagement of the shaft and thereby permits free rotative movement of the pinions on the racks 45.

It is thought that the invention and numerous of its attendant advantages will be understood from the foregoing description and it is obvious that numerous changes may be made in the form, construction and arrangement of the several 5 parts without departing from the spirit or scope of the invention, or sacrificing any of its attendant advantages, the form herein described being a preferred embodiment for the purpose of illustrating the invention.

The invention is hereby claimed as follows:

1. In a shade or blind member arranged for vertical movement in a frame or the like, a control bar extending across said shade or blind, a shaft arranged adjacent said control bar, a gear 15 on said shaft, rack means on the side of the frame engaging said gear, interlocking means between said shaft and said bar for locking the bar and preventing rotation thereof, and release means operated to permit rotation of the gear 20 and allow for freedom of operation of the member.

2. In a shade or blind member arranged for vertical movement in a frame or the like, a control bar extending across said shade or blind, a shaft arranged adjacent said control bar, a plurality of gears on said shaft, rack means on said frame engaged by said gears for maintaining the bar always in the same angular position, interlocking means between said shaft and said bar 30 for locking the bar to prevent rotation of said gears to hold the member in any preselected vertical position, and release means to disengage the interlocking means to permit rotation of said gears and allow free movement of the member.

3. In a shade or blind member arranged for vertical movement in a frame or the like, a tubular control bar secured transversely to the shade or blind adjacent the bottom portion thereof, a transverse shaft arranged adjacent said control bar, a pinion on said shaft, rack means on said frame engaged by said pinion for maintaining the bar and consequently the member always in the same angular position, interengaging means between said shaft and said bar for locking the bar to permit rotation of the shaft and pinion to hold the member in any preselected vertical position, and release means operated to release and disengage the interengaging means to permit free rotation of said pinion and allow 50 freedom of movement of the member.

4. A blind or curtain member comprising a guideway, a rack in said guideway, a revolvably mounted rod for said member, a gear on said rod and having meshing engagement with the rack, 55 means normally preventing rotation of said rod whereby to lock said member and prevent movement of the gear on the rack, and release means manually operated to permit rotation of the rod and permit movement of the gear on the rod and consequently allow for freedom of operation of the member.

GEORGE D. DODGE.
